[57] CLAIM

The ornamental design for a combined egg box and cover, as shown and described.

DESCRIPTION

FIG. 1 is a top perspective view of a combined egg box and cover, showing my new design;
FIG. 2 is a side elevational view thereof, the opposite side being identical in appearance;
FIG. 3 is an end elevational view thereof, the opposite end being identical in appearance;
FIG. 4 is a top plan view thereof;
FIG. 5 is a bottom plan view thereof; and
FIG. 6 is an exploded top perspective view thereof.
The material of the egg box is of substantially uniform thickness throughout, so that the top plan view of the interior of the box is substantially the reverse of FIG. 5.

FIG. 1

FIG. 2

FIG. 3
